Patent expires September 6, 1965

7 Claims. (Cl. 128—2.1)

1

The present invention relates to rheocardiographic apparatus adapted to measure the varying resistance of a living body as a function of heart beat.

Due to heart activity, the electrical resistance of a human or animal organism exhibits a periodic variation. This resistance variation may be recorded by connecting the body resistance in series with a constant resistance to a voltage source and connecting the ends of the constant resistance to the input of an oscillograph. The oscillogram recorded in this manner provides those skilled in the art with data which is useful in medical diagnosis and research.

It is conventional to employ a high-frequency source for this technique of investigation. Where the high-frequency source is energized from a rectifying supply connected to an alternating-current power line, it has been found that the amplitude of the high-frequency voltage tends to fluctuate with changes in line voltage. Inasmuch as the body resistance variation to be recorded is very small and only in the order of 0.3%, it is important that the high-frequency voltage have an amplitude which is free from fluctuation. Consequently, it has heretofore been the practice to use a battery supply for the high-frequency oscillator, since an amplitude-stabilized oscillator energized by an alternating-current rectifier would entail expensive components and a complex circuit.

The principal object of the present invention is to provide an improved rheocardiographic apparatus.

More particularly, an object of the invention is to reduce the influence of amplitude fluctuation in the high-frequency rheocardiograph oscillator on the body resistance measuring voltage fed to the oscillograph.

Still another object of the invention is to permit energization of an ordinary high-frequency oscillator for the rheocardiograph from a power line by means of a conventional rectifier and filter voltage supply.

In accordance with the invention a first high-frequency current is derived from a high-frequency oscillator which is conducted through a living body, whereby the first current is modulated as a function of body resistance. Also taken from the high-frequency oscillator is a

second high-frequency current which is independent of body resistance, the second current being fed into a fixed resistance through which also flows the first high-frequency current modulated by the body resistance; the second current being applied in a phase relative to the first current at which unwanted amplitude fluctuations tend to cancel out.

For a better understanding of the invention, reference is had to the following detailed description to be read in conjunction with the annexed drawing which is a schematic illustration of a rheocardiograph circuit in accordance with the invention.

15 The carrier current source for the rheocardiograph is constituted by a conventional high-frequency oscillator including an electron discharge tube 1, a condenser 2 connected in parallel with a resistor 3, and a coil 4 connected at one end to grid of tube 1 and through condenser 2 to cathode thereof. A direct voltage supply is provided whose positive terminal is connected through the parallel combination of a condenser 5 and a coil 6 to anode of tube 1, the negative terminal being connected to cathode. The direct voltage may be obtained from any conventional rectifying and filter circuit energized from an alternating-current power line.

20 The grid coil 4 and the anode coil 6 are inductively coupled to one another in regenerative relationship by way of a center-tapped output coil 7, whereby a high-frequency wave is sustained in the oscillator.

25 The high-frequency carrier voltage induced in coil 7 is divided into two components in phase opposition. One component yielded in the upper half of coil 7 is applied to the body electrodes connected to terminals 10 and 11 via a coupling capacitor 34 and an output resistor 23, whereas the other component is applied across output resistor 23 via a coupling capacitor 35 and a comparison resistor 9. For the time being the resistance 36 may be considered to be shorted out of circuit by closing the switch 37 shunted thereacross. The resistance of resistor 9 is preferably made equal to the mean value of the body resistance between electrodes 10 and 11.

30 Thus a bridge circuit is formed in which a first branch is constituted by the upper half of coil 7 connected through condenser 34 in series with

2

the body resistance appearing between terminals 10 and 11, and a second branch constituted by the lower half of coil 7 connected through condenser 35 in series with comparison resistor 9, the two branches being connected in parallel relation across output resistor 23.

Since the high-frequency voltages applied to the two branches by the two halves of coil 7 are, despite any fluctuations therein, of equal amplitude but of opposing phase, should the body resistance at any instant be equal to the fixed value of comparison resistor 9, the resultant branch voltages applied across output resistor 23 would cancel each other and a null voltage would be produced thereacross. Therefore, as the value of the body resistance changes as a function of the heart activity, a similarly modulated measuring voltage is developed across resistor 23.

The measuring voltage developed across resistor 23 is applied to a diode rectifier 13 via a condenser 12, a leak resistor 14 being connected across condenser 12 to ensure that variations similar to those in the body resistance occur in the voltage of the condenser. The detected potential across condenser 12 comprises a direct-current component having superimposed thereon a varying component whose variation corresponds to the modulation of the high-frequency carrier voltage developed across resistor 23 by reason of the changes occurring in the body resistance.

This varying component develops an alternating-current drop across resistor 15 which is connected by means of multi-contact selector switch 28 in series with one of condensers 25, 26 or 27 across resistor 15. The voltage developed across resistor 14, however, exhibits a high-frequency component by reason of the high-frequency carrier in the measuring voltage. The voltage set up across resistor 16 is filtered with respect to said high-frequency component by a condenser 17 connected serially with resistor 18 across resistor 16. The influence of the heart beat on the electrical resistance of the body is represented by the alternating voltage developed across condenser 17 in which the high-frequency carrier component is substantially by-passed. This voltage is applied to the input terminals of an oscillograph 19 in which it is impressed on the grid of an amplifier tube 20. The oscillograph which is not otherwise disclosed may be of conventional design, and operates to record the measuring voltage variations subsequent to amplification.

Since the characteristic curve expressing the functional relationship between the anode voltage and the current of diode 13 is not straight but approximately parabolic, the relationship existing between the input voltage of the oscillograph taken from the output of the diode and the input voltage applied to the diode is not linear. In order to ensure a linear relationship between the input voltage of the oscillograph and the varying body resistance, resistor 9 may be given a value differing from the mean resistance of the body. In this case the measuring voltage no longer fluctuates about the zero value but has a constant component so that the working point of the diode is shifted from the curved portion of its parabolic characteristic to the substantially straight line portion thereof.

This expedient has an additional advantage in that it is not necessary at each test to bring the value of comparison resistor 9 into correspondence with the body resistance, it being pos-

sible to operate without changing the value of the comparison resistor. For this purpose comparison resistor 9 is preferably given a value which is smaller than the smallest body resistance that may be expected. Favorable results are obtainable by the use of a comparison resistor whose value is about 20% smaller than the mean resistance of the body.

The use of the above-described bridge circuit also tends to neutralize the influence of so-called "shot effect" in the oscillator tube.

Condensers 25, 26 and 27 have different capacities and are selectively inserted into the filtering circuit by means of selector switch 28. This adjustable filtering circuit makes it possible to pass a desired alternating voltage component and to reject those of different frequency. This is useful for the purpose of neutralizing, for example, the influence of respiration on the record to be produced, for the volume variation due to respiration also brings about resistance variations in the muscular system of the body, which variations, however, exhibit a frequency different from that arising from the heart beat.

In order to minimize the ripple effect on the record arising from the alternating-current (usually 60 cycles) power line serving to energize the power supply for the high-frequency oscillator, provision is made of a voltage divider 29 connected to the terminals 30 and 31 connected to the A-C. power line. The movable tap of this divider is connected to the filtering circuit (16 and 25, 26 or 27) via a resistor 32 and a phase shifter 33. By correctly positioning the tap, an alternating voltage is applied to the filtering circuit which compensates for the alternating current ripple introduced into the system via the high-frequency oscillator. The phase shifter 33, which may be of conventional design, acts to displace the phase of the alternating voltage derived directly from the line to effect cancellation with respect to the alternating voltage ripple derived from the high-frequency oscillator.

The condensers 34 and 35 act to block the voltage generated in the body itself by the heart beat (the voltage used for making the ordinary electrocardiogram) away from the body resistance recording. The capacities of these condensers must be sufficiently low to cause the strength of the alternating current generated in the body to be negligible as compared to the intensity of the high-frequency current supplied by the high-frequency oscillator, but sufficiently high to pass the latter current to a sufficient degree. To facilitate this discrimination, the operating frequency of the high-frequency oscillator must substantially exceed the frequency of the heart beat.

It may be desirable, in some cases, to ascertain the phase relationship existing between the rheocardiogram representing the change in body resistance as a function of heart beat and the electrocardiogram representing the change in body generated voltage as a function of heart beat. This may be effected by short circuiting the blocking condensers 34 and 35, or by substituting therefor relatively high capacity values, whereby the voltage from the high-frequency oscillator is effectively combined with the body generated voltage and impressed across body electrodes 10 and 11 to produce a composite record. In this case, the so-called R-peak of the electrocardiogram also manifests itself in the rheocardiogram.

No measures need be taken to keep the operating frequency of the oscillator constant. This frequency may vary within wide limits. It will preferably not be made lower than 5 kc. in order that the excitation of the nervous and muscular system may remain below the limit of observation. In addition, the frequency should not be excessively low since otherwise the pass resistance at the electrodes and the resistance of the skin increase to an extent such that the resistance variation becomes excessively low relative to the overall resistance.

On the other hand, it is not desirable to cause the frequency to exceed a given value since otherwise particular precautions must be taken to overcome difficulties incidental to the use of very high frequencies. For this reason it is preferable that the operating frequency lie below 50 kc.

Resistance 36, shunted by switch 37 serves for calibration purposes. Upon opening of switch 37, the resistance of the circuit is increased. This produces a jump in the diagram to be recorded and by measuring the height of the jump calibration may be performed.

It is obvious that many changes and modifications may be made in the above-described embodiment without departing from the spirit and scope of the invention.

What we claim is:

1. In apparatus for indicating the variations in the electrical resistance of a living body due to heart action, the combination which comprises a high-frequency voltage source, a resistance element, a comparison resistor, means to impress a first voltage derived from said source through said body across said element thereby to develop a high-frequency voltage across said element modulated in accordance with the variations in the resistance of said body, and means to impress a second voltage derived from said source and of an amplitude equal to said first voltage through said comparison resistor across said element in phase opposition to said first voltage whereby the resultant modulated voltage established across said element is substantially independent of fluctuations in said source.

2. In apparatus for indicating the variations in the electrical resistance of a living body due to heart action, the combination which comprises a high-frequency voltage source and including a center-tapped output impedance, a comparison resistance, an output resistance, and a bridge circuit including one branch constituted by one half of said output impedance in series with the resistance of said body and another and parallel branch constituted by the other half of said output impedance in series with said comparison resistance, said output resistance being shunted across the parallel branches of said bridge whereby the high-frequency voltage developed thereacross has a modulation component depending on the variations in the resistance of said body and substantially independent of fluctuation in said source.

3. An arrangement, as set forth in claim 2, wherein said comparison resistance has a value which is lower than the lowest value of said body resistance.

4. Apparatus for recording the variations in the electrical resistance of a living body due to heart action comprising a high-frequency voltage source and including a center-tapped output impedance, a comparison resistance, an output re-

sistance, a bridge circuit including one branch constituted by one half of said output impedance in series with the resistance of said body and another and parallel branch constituted by the other half of said output impedance in series with said comparison resistance, said output resistance being shunted across the parallel branches of said bridge whereby the high-frequency voltage developed thereacross has a modulation component depending on the variations in the resistance of said body, an oscilloscope, means to detect and filter the voltage developed across said output resistance to produce a potential whose magnitude depends on said modulation component, and means to apply said potential to said oscilloscope.

5. An arrangement, as set forth in claim 4, wherein said detection and filter means includes a diode rectifier connected in series with a first resistor across said output resistance, whereby developed across said first resistor in a rectified voltage having a direct-current component having superimposed thereon a modulation component, and a condenser connected in series with a second resistor across said first resistor, whereby developed across said second resistor is solely said modulation component.

6. Apparatus for recording the variations in the electrical resistance of a living body due to heart action comprising an oscillator producing a high-frequency voltage and including a center-tapped output coil, a comparison resistance, an output resistance, a bridge circuit including one branch constituted by one half of said output coil in series with the resistance of said body and another and parallel branch constituted by the other half of said output coil in series with said comparison resistance, said output resistance being shunted across the parallel branches of said bridge whereby the high-frequency voltage developed thereacross has a modulation component depending on the variations in the resistance of said body, an oscilloscope, means to detect and filter the voltage developed across said output resistance to produce a potential whose magnitude depends on said modulation component, and means to apply said potential as an input to said oscilloscope.

7. An arrangement, as set forth in claim 6, wherein said oscillator is energized from a low-frequency alternating current supply, and further including means to derive a low-frequency voltage from said supply and to apply it to the input of said filter means in such phase as to cancel the low-frequency component appearing therein.
